Patented Aug. 10, 1920.

UNITED STATES PATENT OFFICE.

JAMES McALLAN, OF TORONTO, ONTARIO, CANADA.

BEDSTEAD.

1,349,287.

Specification of Letters Patent. Patented Aug. 10, 1920.

Application filed December 9, 1919. Serial No. 343,526.

To all whom it may concern:

Be it known that I, JAMES McALLAN, residing at Toronto, in the county of York, in the Province of Ontario, Canada, have invented certain new and useful Improvements in Bedsteads, of which the following is the specification.

My invention relates to improvements in bedsteads and the object of the invention is to devise a simple and cheap construction which may be easily assembled and disassembled whenever desired with a minimum amount of labor and it consists essentially of the arrangement and construction of parts as hereinafter more particularly explained.

Figure 1 is a perspective view of my bedstead.

Fig. 2 is an enlarged longitudinal sectional detail through the major portion of the bedstead intermediately broken away of its length.

In the drawings like characters of reference indicate corresponding parts in each figure.

1 indicates the bed head and 2 the bed foot. The bed head 1 is provided with the usual pillars 3 and 4 connected together by cross bars 5, 6, 7 and 8. The foot 2 is provided with pillars 9 and 10 which are connected together by suitably arranged cross bars 11, 12, 13 and 14. The head and foot of the bed 1 and 2 are connected together by upper bars 15 and 16 provided at one end with hooks 17 and 18 which rest upon the cross bar 7 and at the opposite end with hooks 19 and 20 which rest upon the cross bar 13. 21 and 22 are lower spacing bars extending longitudinally of the bed and provided at one end with hooks 23 which rest upon the cross bar 8 and at the opposite end with hooks 24 which rest upon the cross bar 14.

It will thus be seen that the bars 15 and 16 and 21 and 22 hold definitely spaced apart the head 1 and foot 2 of the bed and in a vertical position.

25 and 26 are hook brackets which are secured to the pillars 3 and 4 of the head 1. 27 and 28 are hook brackets which are secured to the pillars 9 and 10 of the bed foot 2. The recesses of the hooks 25, 26, 27 and 28 are rectangular and 29 and 30 are rec-

tangular bars which fit into the recesses of the hook brackets 25, 26, 27 and 28. 31 is a woven wire mattress fabric which is secured at one end to the bar 29. 32 is a bar which is secured to the free end of the mattress fabric 31 and extends crosswise of the bed. 33 are rods provided at their outer ends with threaded portions 34 (see Fig. 2) and at their inner ends with flattened portions 35 which are riveted to the cross bar 32. 36 are orifices which extend through the bar 30 and through which the rods 33 extend. 37 are wing nuts which are screwed onto the outer ends of the rods 33 against the outer ends of the bar 30. By screwing up the wing nuts upon the rods 33 the free end of the mattress is drawn so as to stretch it, the opposite end of the mattress being held in a rigid position by the cross bar 29. In order to reinforce the edges of the mattress I rivet thin bars of metal 39 on to the upper face of the mattress in proximity to its edge and similar bars 40 to the lower face of the mattress opposing the aforesaid bars. The bars 39 and 40 are divided at 41 so as to allow of the free movement of the central portion of the mattress, the divided ends of the bars being drawn slightly apart as the mattress is stretched by the tightening of the wing nuts 37.

From this description it will be seen that I have devised a very simple form of bedstead which may be readily disassembled all that it is necessary to do being to loosen the wing nuts 37, the bars 29 and 30 are lifted out of engagement with the brackets 25 and 26 and 27 and 28 thereby disengaging the mattress from the bed. The bars 21 and 22 and 15 and 16 are then lifted out of engagement with the cross bars 8 and 7 and 14 and 13 thereby separating the head and foot of the bed, 1 and 2 respectively. The bed is then ready for shipment. In order to assemble the bed the reverse of this operation is performed.

It will also be seen that by my construction I dispense with the mattress frame which is usually employed thereby cheapening the construction.

What I claim as my invention is.

The combination with a bedstead, of a cross bar removably carried by the head section of the bedstead, a second cross bar

removably carried by the foot section of the bedstead, a fabric mattress attached at one end to said first-mentioned cross bar, a cross bar carried by the free end of said fabric mattress and adjustably secured to said second mentioned cross bar, and pairs of reinforcing bars extending longitudinally along

the top and bottom of the mattress at the side edges thereof, the pairs of bars extending along each side edge of the mattress 10 being disposed on opposite sides of the transverse center of the mattress, so as not to interfere with the stretching thereof.

JAMES McALLAN.
